AGGREGATE SPREADER

William J. Slavin, Howell, Mich.

Application October 18, 1938, Serial No. 235,651

4 Claims. (Cl. 94—44)

This invention relates to aggregate spreaders and the object of the invention is to provide a device for spreading aggregate in uniform volume per lineal foot of road surface.

Heretofore, it has been usual in attempting to salvage loose material secured in scraping a road surface to try to estimate the amount of aggregate required at various points to approximate amount of aggregate required to provide for uniform volume per lineal foot of road surface and usually such estimate of added aggregate is too high or too low and therefore even with considerable care, the spread material will not be uniform per lineal foot of road surface but will vary considerably in different sections thereof. By use of my improved aggregate spreader, a uniform volume of aggregate per lineal foot of road surface is provided by maintaining the spreader practically filled by adding aggregate to the salvaged material accumulated therein by drawing the spreader over the road surface so that the salvaged road material with the new aggregate deposited in the spreader will be spread in uniform depth per lineal foot over the road surface.

One of the particular objects of the invention is to hold the aggregate spreader down onto the road surface to prevent it from climbing up over any loose aggregate and causing variation in delivery of the amount of aggregate per lineal foot of road surface.

Another object of the invention is to hold the spreader to the road surface by the movement of portions of the spreader through the aggregate.

These objects and several novel features of the invention are hereinafter more fully described and claimed and the preferred form of construction by which these objects are attained is shown in the accompanying drawing in which—

Fig. 1 is a side elevation showing my improved aggregate spreader in association with the dump truck from which a supply of aggregate may be continuously delivered to the spreader.

Fig. 2 is a plan view of my improved aggregate spreader.

Fig. 3 is a side elevation thereof.

Fig. 4 is a section taken on line 4—4 of Fig. 2.

Fig. 5 is a section taken on line 5—5 of Fig. 2.

In Fig. 1, an ordinary dump truck is shown having the body 1 tilted in the usual manner hereby suggested as a tilting element 2 which may be of any desired form and which may vary the angle of the dump body relative to the horizontal. This body has the usual pivoted end gate 3 which may be controlled in position to vary the rapidity with which the truck body may dis-

charge the material. The aggregate spreader is indicated generally at 4 in Fig. 1 and the material deposited is shown at 5 in said figure.

The aggregate spreader can be conveniently formed of upper and lower frame elements 6 and 7, shown in Fig. 3, and the vertical bars 8 and 9 on both sides of the device are similarly formed and at the lower frame 7 of each side member *a* and *b* is provided with a shoe or runner 10. The two side members are practically identical in form and preferably, the upper and lower frames 6 and 7 are angle bars and likewise the vertical members 8, 8' and 9 to form stiff side members. On the inner faces of these frame elements 6, 7, 8, 8' and 9 are mounted metal plates 11 and 12.

The two side elements *a* and *b* are secured together at the front end by a rod 13 which extends through the vertical frame members 9 at the forward end and between the side plates 12 is a tubular member 14 on the rod 13 and the nuts 15 may be tightened up thus clamping the plates 12 between the nuts and the end of the tubular member 14 on the rod 13. To this tubular member 14 are attached the drag chains 16 and these drag chains are attached to the rear end of the dump truck in any approved manner and closely coupled therewith so that by tilting the dump body 1, with the gate 3 open to a predetermined extent, the aggregate in the dump body discharges into the spreader between the plates 12 and onto the road surface about or slightly more than the quantity required.

It is noted that the plates 12 at the forward end of the framework are outturned and form the inclined flanges 17. This outwardly inclined flange portion 17 of the plates 12 prevents material discharging from the dump body from spilling outside of the aggregate spreader as may be readily understood.

The rear ends of the side members *a* and *b* are connected together by a channel bar 18 which is bolted at its opposite ends to the rear vertical frame elements 8' and the lower flange 19 of the channel bar 18 is positioned at a point above the possible required level of the spread material.

I provide further a striker plate 20 shown in Fig. 5. This striker plate is approximately the same length as the distance between the plates 11, shown in Fig. 3, of the opposite side elements *a* and *b* and sufficiently less in length to permit ready adjustment of the striker plate.

Secured to the lower edge of the striker plate 20 is a striker bar 21 which is simply an angle bar of greater length than the plate 20 and extends over the vertical angle bars 8' at opposite ends 55

as shown particularly in Fig. 2. Each of the vertical bars 8' has a slot 23 to receive a bolt 22, and the bolts passing through the apertures in the bar 21 pass through the slots 23 and by loosening 5 the nuts on these bolts the plate may be raised or lowered to vary the height of the lower flange of the bar 21 from the road surface. To adjust the striker plate vertically, a bolt 34 is inserted through apertures provided therefor in both 10 flanges of the channel bar 18 as shown in Fig. 4 and a collar 35 is secured to each bolt beneath the top flange. This allows rotation of the bolt but prevents vertical movement thereof in either direction. The lower end of the bolt extends 15 through the flange 21 of the striker plate and a nut 36 is welded or otherwise secured to the flange 21 for each bolt so that as the bolts are rotated the nuts are caused to travel up or down the threads to raise and lower the striker plate.

20 The striker plate 23 is further provided with a vertical slot 24 at the center and a bolt 25 extends through the channel bar 18 and the slot 24 thus supporting the striker plate 23 in its mid-section. For adjustment, the bolts 22 and 25 are loosened and the bolts 34 may be turned to raise or lower the striker plate to the desired 25 position, at which time, the bolts 22 and 25 may be tightened to lock the striker plate in position.

By use of this angle bar 21 at the lower edge 30 of the striker plate, there is a flat under surface 26 as shown in Fig. 3 that forms the top surface of the deposited material and while the material may pile up to a much greater depth within the spreader it will of necessity only feed out of 35 the spreader as the spreader is moved by the dump truck and as the material is held within the side walls *a* and *b*, these walls form the vertical edges of the deposited row of material and the striker bar face 26 forms the top surface and thus provides for a practically uniform cross 40 section of material deposited at any point of the road surface.

In depositing the material from the truck into 45 the aggregate spreader, the tail gate 3 of the truck is set to the desired opening by means of a chain 37 shown in Fig. 1 and the body is tilted to its maximum angle. By regulating the 50 position of the tail gate 3, the flow of material per unit of time may be controlled to secure a greater or less rapidity of flow of material into the aggregate spreader.

It will be obvious from the foregoing that the 55 aggregate spreader as associated with a dump truck may deposit a variable volume of new material in relation to the salvaged material on the road bed.

In building oil mix and stabilized roads by the 60 road mix or travelling plant method, it is desired to conserve all possible utilizable material and thus the method of road building which 65 may be pursued in the use of my improved apparatus and associated with a dump truck after the general manner shown is as follows:

Firstly, gravel roads are usually covered with 65 more or less loose gravel and are rutted especially after a period of use in which re-surfacing is required. Therefore, my improved method involves firstly the scraping of the road bed by scrapers usually used for this purpose to secure 70 an even surfaced hard bed. This loose aggregate is scraped into a windrow on the road and is hereinafter termed "salvaged" material. It is important that the exact required amount of new and salvaged aggregate be uniformly placed upon 75 the road bed before the application of the bitu-

minous or other binder. My aggregate spreader straddles the windrow of the salvaged aggregate and new aggregate from the dump truck is discharged into the aggregate spreader as it is moved forward. The adjustable gate or striker plate 20 is set to permit the required amount of new and salvaged aggregate per lineal foot of road surface to pass.

As the dump truck and aggregate spreader are 10 moved forward over the windrow, the new material from the dump truck is added to the windrow of salvaged material and as a little more material is maintained in the aggregate spreader than is spread on the road, the full volume of aggregate per lineal foot of road is deposited on 15 the road bed irrespective of what the proportionate volume of the salvaged material and new material may be. Thus, if a portion of the windrow is narrow, a greater amount of new material is automatically added at this point 20 while if the windrow is wide a less amount of new material is added. In order to accomplish this result, it is necessary that the tail gate be 25 carefully set to keep the aggregate spreader practically full of material in order that a uniform width and height of aggregate may be produced from the combined salvaged and added aggregate.

In order to hold the aggregate spreader down 30 firmly on the road surface and prevent the aggregate from working out under the runners 10 and causing the spreader to climb up on the loose aggregate, I have provided a pair of angle iron members 38 and 39 shown more particularly in Figs. 3, 4 and 5. Each angle iron member 38 35 and 39 is provided with a flat metal strip 40 secured to one flange thereof and extending outwardly into the spreader. Each of these angle iron members is pivotally supported on a bolt 41 mounted in the side plates 12 and the corresponding side plates 11 are provided with apertures 42 at the opposite end of the respective angle iron member through which a bolt 43 may be inserted to secure the rear end of the respective angle iron member in place. By turning 45 either angle iron member on its pivot 41 the bolt 43 may be secured in any one of the series of bolt holes 42 to vary the angularity of the angle iron member and plate 40. These two plates 46 extending at an angle as shown are buried 50 in the aggregate when the aggregate spreader is filled and as the aggregate spreader is drawn forward the weight of the aggregate moving up the inclined metal strips 40 holds the spreader firmly down to the road surface and prevents 55 any tendency of the spreader to climb or move upwardly over the loose aggregate. These metal strips 40 may be adjusted in angularity by means of the bolt holes 42 to provide the desired pressure to hold the spreader down to the road surface as it is drawn forward by the dump truck. This produces the effect of adding considerable weight to the spreader as the plates 46 move 60 through the aggregate and insures the spreader remaining at the level of the road surface and 65 delivering the desired volume of aggregate per lineal foot of road surface.

As the loose aggregate is delivered into the spreader and as the spreader has no bottom it is necessary to provide such means for holding the 70 spreader down to the road surface and prevent it from climbing the aggregate and delivering a greater volume of aggregate than desired.

Methods heretofore used have been to dump 75 the aggregate on the road bed as near uniformly

as could be determined but in such previous methods a variation of ten to twenty percent in quantity per lineal foot of road bed is possible and such variation is sufficient to cause an unstable mixture and a resultant failure of the road surface due to its being productive of a variable percentage of bitumen in the mix tending to cause raveling or corrugating of the finished road surface which is one of the most common causes 5 of failure of the bituminous road surfaces or road surfaces of the oil mix type. The bitumen is finally applied to the spread aggregate at a uniform rate in the usual manner which requires a uniform quantity of aggregate per lineal foot of 10 road surface to secure a road surface containing a uniform percentage of bitumen.

It is also to be noted that the channel bar 18 is supported from deflection in its mid-section by means of the bars 30 and 31, the bar 30 being 15 attached at 32 to the top flange of the upper frame element 6 of the side b and the other bar 31 is likewise attached to the top member 6 of the side a. The opposite ends of these bars extend to and are jointly bolted by means of a bolt 33 to approximately the center of the top flange of the member 18 and thus support the member 18 and side walls a and b from material deflection when the device is dragged along a road and practically full of aggregate.

30 It is to be noted that the device may be easily disassembled and moved from one job to another and saves labor and material in road building.

It is believed evident from the foregoing that the apparatus—namely, the dump truck and 35 aggregate spreader associated therewith by which dump truck the aggregate spreader is moved over salvaged aggregate and additional aggregate added as the aggregate spreader is moved to thereby secure the desired uniform volume of 40 aggregate per lineal foot of road surface, that, by the features of construction of the aggregate spreader and association with the dump truck and body, the material is prevented from discharging from the dump body to outside the confines of 45 the walls of the aggregate spreader, that the aggregate spreader is firmly held down to the road surface as it is drawn through the aggregate and that the various features and objects of the invention are attained by the construction and 50 arrangement of the parts as described and utilized in my improved method of forming a road surface.

Having thus fully described my invention, its utility and mode of operation, what I claim and 55 desire to secure by Letters Patent of the United States is:

1. A spreader for use in distributing aggregate upon a prepared road surface, comprising a rectangular box-like structure having side walls and 60 a rear wall and being open at the bottom, top and front, the rear wall including an adjustable end gate, means for adjusting the end gate vertically to vary the distance of the lower edge from the ground surface, an angle iron member pivotally 65 mounted on the inner side of each side wall adjacent the forward end thereof, the rear end of each side wall being provided with a series of bolt apertures, a bolt carried by the rear end of each angle

iron member and arranged to be secured in any one of said apertures, the apertures being arranged to vary the angularity of the angle iron member on the side wall and a plate secured to each angle iron member and extending inwardly from the side wall at a right angle to the plane thereof, the arrangement being such that as the spreader is drawn through the aggregate the aggregate is caused to ride up on the sloping plates.

2. A spreader for use in distributing aggregate upon a prepared road surface, comprising a rectangular box-like structure having side walls and a rear wall and being open at the top, bottom and front, the rear wall including an adjustable end gate, means for adjusting the end gate vertically to vary the distance of the lower edge from the ground surface, a pair of angle iron members extending lengthwise of each side wall, a plate secured to each angle iron member and extending inwardly from the side wall, means for adjusting one end of each angle iron member upwardly or downwardly to vary the slope of the angle iron members and plates longitudinally of the side walls, the arrangement being such that as the spreader is drawn through the aggregate the aggregate riding up the sloping plates holds the spreader down onto the road surface.

3. A spreader for use in distributing aggregate upon a prepared road surface, comprising a rectangular box-like structure having side walls and a rear wall and being open at the top, bottom and front, the rear wall including an end gate, means for adjusting the end gate vertically to vary the distance of the lower edge from the ground surface, a plate like element on each of the opposite side walls each extending inwardly therefrom toward the other, means pivotally supporting the forward end of each of the plates on the respective side walls near the lower edge, said plates being in parallel relation and being upwardly inclined from the open front end of the spreader toward the rear whereby, as the spreader is moved, the aggregate rides the inclined faces of the plate and tends to maintain the front end of the spreader in contact with the road surface, and means for adjusting the plate like elements about the respective pivots to vary the angle thereof relative to the horizontal.

4. A spreader for use in distributing aggregate upon a prepared road surface, comprising a rectangular box-like structure having side walls and a rear wall and being open at the top, bottom and front, the rear wall comprising an end gate, means for adjusting the end gate vertically to vary the distance of the lower edge from the ground surface, and a member adjustably secured to the inner side of each side wall and extending inwardly at a right angle to the plane of the side wall, the two said members being in substantially parallel relation and being upwardly inclined from the forward open end of the spreader toward the rear and having upper faces on which the material entering the spreader may ride to thereby maintain the forward end of the spreader on the ground surface.

WILLIAM J. SLAVIN.
